UNITED STATES PATENT OFFICE.

EDWARD F. SHUE, OF NEW YORK, N. Y.

FENDER.

1,108,801.

Specification of Letters Patent. Patented Aug. 25, 1914.

Application filed January 11, 1913. Serial No. 741,488.

To all whom it may concern:

Be it known that I, EDWARD F. SHUE, a citizen of the United States, residing at New York, in the county of New York and State 5 of New York, have invented new and useful Improvements in Fenders, of which the following is a specification.

This invention relates to fenders, the object in view being to improve and carry forward, as well as simplify, the construction 10 illustrated and described in my former Patent, No. 960,120, dated May 31, 1910.

The main object of the present invention is to provide means for quickly thrusting 15 outward a normally folded and concealed fender on an automobile or self-propelled vehicle, the means for performing the thrusting action being releasable instantly by the driver, without moving from his seat 20 or ordinary driving position.

A further object of the invention is to cushion the spreading movement of the fender, and also lock the same against recoil, after reaching its outermost position.

25 A further object is to provide means for rewinding the spring which acts as the motive power for thrusting out the fender to its spread or operative position.

With the above and other objects in view, 30 the invention consists in the construction, combination and arrangement of parts, as will be hereinafter more fully described, illustrated in the accompanying drawings, and pointed out in the claims hereunto appended.

In the drawings: Figure 1 is a vertical longitudinal section through the sheath at 40 one side of the fender, embodying the present invention, and showing the fender folded. Fig. 2 is a similar view, showing the fender spread. Fig. 3 is a cross section taken on the line 3—3 of Fig. 1. Fig. 4 is a cross section taken on the line 4—4 of Fig. 3. Fig. 5 is a cross section through the 45 bumper rod at the front end of the fender, showing the attaching clips for securing the flexible apron thereto. Fig. 6 is a front elevation of one of the upright sheaths. Fig. 7 is a detail section showing the means for rewinding the fender actuating spring without leaving the driver's seat. Fig. 8 is a detail section on the line 8—8 of Fig. 1.

Referring to the drawings, 1 designates one of the side bars of the chassis of an automobile, to which is fastened in any con-

venient manner a tubular sheath 2 extending longitudinally thereof, and secured to the outer face of the bar 1. It may be stated here that two of the sheaths 2 are employed, one on each side of the machine, and 60 in each of said sheaths there is arranged a slideable element 3 for thrusting outward the arms which spread the flexible apron constituting the body of the fender into position to receive a person or object, in the 65 path of the automobile.

Each of the slideable elements 3 is in the form of a rack bar or rod provided along its upper side with teeth 4, which are engaged with and driven by a pinion 5. Two of these 70 pinions 5 are employed, the same being connected to a common shaft 6 which extends across the machine at a convenient point, preferably under the inclined floor 7 upon which the driver places his feet, said inclined floor extending from the main floor 8 upward to the dash, shown at 9.

Each of the pinions 5 is mounted in a gear casing 10 secured by means of rivets 11 or their equivalent to the adjacent bar 1 of 80 the chassis, said gear casing also having a stud 12, on which is journaled a supporting roller 13, the periphery of which is grooved to receive the rod or slideable element 3, as clearly indicated in Figs. 1 and 2.

Connected pivotally at 14 to the forward extremity of the slideable element 3 is one of a pair of lower spreader arms 15 which extend outwardly through the advance ends of the sheaths 2, and are connected at their forward extremities by a bumper bar or rod 16, preferably tubular to give the necessary resiliency thereto, the forward end of each spreader arm 15 being split or divided, as shown at 17, forming a comparatively thin 90 and bendable strap which embraces the bumper 16 and is fastened by means of a screw 18, thereby adapting the bumper 16 to be placed in position and securely clamped to the lower spreader arms.

Near the forward end of each spreader arm 15, there is also attached a ground supporting roller 19, preferably equipped with a rubber tire 20, and carried by a fork 21 which is swiveled in the adjacent spreader 105 arm 15, as shown at 22, thereby enabling said wheel to act like a caster and run along the ground, while supporting the forward extremity of the lower spreader arm to which it is attached.

Extending upward from the advance end of each sheath is an upright sheath 23, the same being rigidly attached to the lower horizontal sheath. Pivotally mounted, at 24, near the upper end of each of said upright sheaths 23 is an elbow lever, comprising a spreader arm 25, and an operating arm 26, the two levers referred to being connected by a cylindrical housing 27, in which is arranged a spring roller 28 having wound thereon a flexible fender apron 29, one end of which is attached to said roller, while the other end is attached to a stretcher bar 30. This stretcher bar 30 has connected thereto a plurality of clips 31, the latter being secured to the stretcher bar 30 by means of clamping screws 32. At their opposite ends, the clips are connected by screws 33 or their equivalent to the tubular bumper 16, hereinabove described.

34 designates a slidable sleeve which embraces the lower spreader arm 15, and has connected thereto the lower end of a cable 35, the upper end of which is attached to a rod 36 slidable through the end cap 37 of a cylindrical casing 38, in which is arranged an expansion spring 39. The rod 36 passes through the spring 38 and is provided with a washer or shoulder 40 which bears against the upper extremity of the spring 39, the casing 38 being itself pivotally connected to the arm 26 at the point 41. The lower spreader arm 15 carries a lug or shoulder 42, and as said arm 15 is thrust outward, the shoulder 42 comes into contact with the sleeve 34 and thereby draws downwardly on the cable 35, pulling the arm 26 downward and carrying the arm 25 upward, the effect of which is to unroll the fender apron and spread the same outward in an inclined position, or in other words, carry said apron from the folded position shown in Fig. 2 outward to the spread-out position shown in Fig. 1.

45 The upright sheath 23 embraces the forward end of the horizontal sheath 2, and is extended below the plane of the last-named sheath, where it is reduced in width, as shown at 43 in Fig. 6, so that when the arm 15 has reached the forward end of its movement, the said arm drops in the downwardly flared socket 43 of the sheath shown in Fig. 2, thereby preventing any lateral moving or swaying of said arm, after the fender is 55 in its operative position.

44 designates a supporting roller located just back of the reduced socket 43 and underlying the spreader arm 15, so as to support the same as it is thrust back and forth.

60 45 designates a guide roller carried by the forward end of the slidable element 3, and operating in the relatively enlarged portion of the sheath, the rear portion of the sheath being of just sufficient size to receive the slidable element 3, the sheath 2 be-

ing slightly enlarged, as shown at 46, to admit of a coiled cushion spring 47 being placed around the member 3, so as to cooperate with the shoulder 48 of the slidable element; just prior to the latter reaching its outermost limit of movement, which serves to cushion such outward movement of the slidable element. The spring 47 is sufficiently larger in diameter than the slid- 75 able element to permit the latter to slide 75 freely through it.

The main winding spring 49 which serves as the actuating device for spreading the fender, is inclosed in a cylindrical housing 50, as shown in Fig. 3, one end of said spring being secured, as shown at 51, to the housing 52 for the shaft 6, while the opposite end of said spring is fastened, as shown at 53, to an internal ratchet wheel 54 keyed or otherwise fastened to the shaft 6, as 85 shown in Fig. 4.

The ratchet wheel 54 is provided upon its outer side with one or more teeth 55 adapted to be engaged by the upper end of a dog 56, the lower or tail end of the dog being 90 shown at 57, and being adapted to be operated upon by a small trip arm 58 fast on the shaft 59 which is provided with an operating crank, 60, so that by turning said crank 60 the dog 56 may be thrown out of engagement with the shoulder 55 on the ratchet wheel to allow the same to be turned, for the purpose of winding up the spring 49.

Mounted loosely on the housing 52 is a dog holder 61, on which are pivotally mounted, at 62, a pair of diametrically opposite dogs 63 having projecting lips 64 movable into and out of engagement with diametrically opposite teeth or shoulders 65 on the inner side of the rim of the ratchet 105 wheel, as shown in Fig. 4. The tail portions 66 of the dogs 63 are adapted to be operated by a pair of oppositely arranged dog releasing shoulders 67 on a cross head mounted loosely on the housing 52, and embodying the oppositely projecting arms 68 which serve, when moved in one direction, to press the dogs 63 outwardly into engagement with the shoulders 65. When said cross head is moved in the opposite direction, the projections or shoulders 67 operate to swing the dogs 63 in the opposite direction.

Connected to the cross head 68 is an arm 69, to which is connected a trip rod 70 which extends upward through the floor 7 above described, and also through a guide tube 71 extending upward from said floor, said rod having attached at its opposite end an operating knob or handle 72. The rod 70 is provided at a suitable point with a notch 73 adapted to be engaged by a spring catch 74 secured to the tube 71, so that when said knob 72 is pulled upward, the catch 74 which is provided in its free end with a 130

hole through which the rod 70 is slidable will snap into engagement with the notch 73 and lock the parts in such position.

Connected to the dog holder 61 is an outwardly extending arm 75, on which the detent 56 is pivotally mounted at the point 76.

77 designates a spring which acts to normally hold the dog or detent 56 into engagement with the tooth or shoulder 55 on the ratchet wheel.

78 designates a detachable hand crank adapted to be applied to the squared end 79 of the shaft 6, for the purpose of winding up the spring 49 in the act of setting the fender.

15 Instead of applying the hand crank 78 to the end of the shaft 6, which requires a dismounting from the machine, the spring may be wound up without leaving the driver's seat, by resorting to the modified form of 20 spring rewinder illustrated in Fig. 7, wherein it will be observed that the ratchet wheel 54 has fastened thereto a bevel gear wheel 80, meshing with a pinion 81 on the lower 25 end of a short shaft 82 having the end thereof squared, as at 83, to receive a detachable crank 84 which extends above the floor of the car within reach of the driver.

85 designates the hanger for the shafts 6 and 82, the same being secured to the floor 30 85' by means of bolts 86.

87 designates a roller journaled in the hanger 85 and bearing against the rear side of the beveled gear wheel 80 for the purpose of holding said gear wheel constantly in 35 mesh with the pinion 81.

In order to release the folded fender, it is only necessary to grasp the knob or handle 72 and pull the same upwardly, until the catch 74 snaps into the notch 73. This pulls 40 upward on the arm 69 and throws the dogs 63 out of engagement with the ratchet wheel, thereby releasing the spring 49 which in unwinding revolves the shaft 6 and the pinion 5, and actuates the rack bars or slidable elements 3 in an outward direction. This 45 forces outward the spreader arms 15, and they in turn, through the medium of the sleeves 34 and connections 35, throw the upper spreader arms 25 forward from the 50 position shown in Fig. 1 to the position shown in Fig. 2. This spreads the fender apron, and stretches the same in condition to receive a person or object in the path of the automobile. Just before the fender 55 reaches its fully spread condition, the cushion springs 47 come into action, and the recoil of said springs is prevented by the detent 56 springing into engagement with the shoulder or tooth 55 on the ratchet wheel.

60 thereby preventing backward movement of the wheel and shaft.

In order to rewind the fender, the hand crank referred to is operated, so as to revolve the shaft 6. Before this is done, however, 65 the crank 60 is moved, so as to throw the

detent 56 out of engagement with the ratchet wheel. This permits the shaft to be turned by the hand crank, and the spring 49 is then rewound to the full extent. At the same time, the slidable elements 3 are retracted by 70 the pinions 5, and the fender as a whole is finally restored to its folded condition. When fully folded, a pair of guard lips 88 forming extensions of the advance ends of the lower spreader arms 15 are moved in 75 front of the housing 27 of the spring roller 28, so as to avoid any tendency of the arm 25 to swing out of place when the automobile is subjected to violent jars.

What is claimed is:

1. A fender comprising parallel slidable elements, a flexible apron, upper and lower apron spreading means actuated by the movement of the slidable elements, a spring for actuating the slidable elements, and a rotary shaft actuated by said spring and geared to the slidable elements. 80

2. A fender comprising parallel slidable elements, a flexible apron, upper and lower apron spreading means actuated by the movement of the slidable elements, a spring for actuating the slidable elements, and means for winding said spring. 90

3. A fender comprising parallel slidable elements, a flexible apron, upper and lower apron spreading means actuated by the movement of the slidable elements, a spring for actuating the slidable elements, and ratchet mechanism for winding said spring. 95

4. A fender comprising parallel slidable elements, a flexible apron, upper and lower apron spreading means actuated by the movement of the slidable elements; a spring for actuating the slidable elements, ratchet mechanism for winding said spring, and 100 means for tripping said spring.

5. A fender comprising parallel slidable elements, a flexible apron, upper and lower apron spreading means actuated by the movement of the slidable elements, a spring for actuating the slidable elements, and means for winding said spring and retracting the slidable elements. 110

6. A fender comprising parallel slidable elements, a flexible apron, apron spreading means actuated by the movement of the slidable elements, a spring for actuating the slidable elements, and means for cushioning the outward movement of the slidable elements. 115

7. A fender comprising parallel slidable elements, a flexible apron, upper and lower apron spreading means actuated by the movement of the slidable elements, a spring for actuating the slidable elements, and means for locking the slidable elements when thrust outward. 120

8. A fender comprising parallel slidable elements, a flexible apron, apron spreading means actuated by the movement of the slid- 130

able elements, a spring for actuating the 5
slidable elements, springs for cushioning the
outward movement of the slideable elements,
and means for preventing the recoil of the
cushioning springs.

9. A fender comprising parallel slideable
elements, a flexible apron, upper and lower
apron spreading arms actuated by the move- 10
ment of the slideable elements, a rotary shaft
geared to the slideable elements, a coiled
spring surrounding and connected to said
shaft, and pawl and ratchet mechanism for
winding and tripping said spring.

10. A fender comprising parallel slideable
elements, a flexible apron, apron spreading 15
arms actuated by the movement of the slideable
elements, a rotary shaft geared to the
slideable elements, a coiled spring surround-
ing and connected to said shaft, a ratchet
20 wheel on said shaft, and means for holding
said ratchet wheel against rotation in either
direction.

11. A fender comprising parallel slideable
elements, a flexible apron, apron spreading 25
arms actuated by the movement of the slideable
elements, a rotary shaft geared to the
slideable elements, a coiled spring surround-
ing and connected to said shaft, a ratchet
30 wheel on said shaft, means for holding said
ratchet wheel against rotation in either di-
rection, and means within reach of the
driver for releasing said ratchet wheel.

12. A fender comprising parallel slideable
elements, a flexible apron, apron spreading 35
arms actuated by the movement of the slideable
elements, a rotary shaft geared to the
slideable elements, a coiled spring surround-
ing and connected to said shaft, a ratchet
40 wheel on said shaft, means for holding said
ratchet wheel against rotation in either di-
rection, means within reach of the driver for
releasing said ratchet wheel, and means for
automatically locking the parts in either
position.

45. 13. A fender comprising parallel slideable
elements, a flexible apron, upper and lower
apron spreading arms actuated by the move-

ment of the slideable elements, a spring for
actuating the slideable elements, and a
bumper carried by the lower spreader arms 50
and having the apron connected therewith
and located in advance of the apron.

14. A fender comprising parallel slideable
elements, a flexible apron, upper and lower 55
apron spreading arms actuated by the move-
ment of the slideable elements, a spring for
actuating the slideable elements, a bumper car-
ried by the lower spreader arms and located
in advance of the apron, and spacing clips
connecting the apron to said bumper. 60

15. A fender comprising parallel slideable
elements, a flexible apron, upper and lower
sets of apron spreading arms actuated by
the movement of the slideable elements, a
spring for actuating the slideable elements, 65
upright sheaths for the upper set of arms,
and resilient connections between the upper
and lower sets of arms.

16. A fender comprising parallel slideable
elements, a flexible apron, upper and lower 70
sets of apron spreading arms actuated by
the movement of the slideable elements, a
spring for actuating the slideable elements,
upright sheaths for the upper set of arms,
resilient connections between the upper and 75
lower sets of arms, and shoulders on the
lower set of arms which act on the resilient
connections at a predetermined point in the
outward thrust of said lower arms.

17. A fender comprising parallel slideable
elements, a flexible apron, apron spreading 80
arms actuated by the movement of the slideable
elements, a spring for actuating the
slideable elements, sheaths for the lower
arms, and inclined and forwardly sloping
sockets for sustaining said arms in an in-
clined position and against lateral move-
ment when thrust outward.

In testimony whereof I affix my signature
in presence of two witnesses.

EDWARD F. SHUE.
